Term of patent 14 years

(Cl. D71—1)

FIG. 1 is a side elevational view of an engine propelled water craft showing our new design, the opposite side being substantially the same in appearance;

FIG. 2 is a top plan view thereof; and

FIGS. 3 and 4 are front and rear elevations respectively, thereof.

The handle and center support therefor are broken away in FIG. 4 for convenience of illustration only.

We claim:

The ornamental design for an engine propelled water craft or similar article, as shown and described.
